UNITED STATES PATENT OFFICE

FAYE B. HAMMOND, OF SCHUYLER, NEBRASKA

WINDOW SHADE AND CURTAIN HOLDER

Application filed June 23, 1927. Serial No. 200,942.

This invention relates to window shade and curtain holders of that type wherein a longitudinally extending rod is provided for supporting the curtain which is detachably engaged with a base plate adapted to be attached to the lintel of the window, the rod and the base plate being longitudinally adjustable so as to fit windows of various sizes and the base plate carrying shade roller supports.

The general object of the present invention is to improve upon the details of construction and arrangement of parts in devices of this character whereby the device may be made very simply, cheaply and strongly.

A further object is to provide improved means whereby the longitudinally extending rod may be engaged with the base plate against any chance of detachment.

Other objects will appear in the course of the following description.

My invention is illustrated in the accompanying drawings, wherein:—

Figure 1 is a face view of a window with my shade support mounted thereon;

Figure 2 is a top plan view of the curtain and shade supporting bracket constructed in accordance with my invention;

Figure 3 is a section on the line 3—3 of Figure 2;

Figure 4 is a section on the line 4—4 of Figure 2;

Figure 5 is a section on the line 5—5 of Figure 2;

Figure 6 is a perspective view of the base portion of the shade and curtain support;

Figure 7 is a perspective view of the curtain supporting rod detached from the base;

Figure 8 is a perspective view of one end of one of the base sections looking at the rear face thereof and with the flanges 13 opened up;

Figure 9 is a perspective view of one of the shade supporting brackets detached from the base.

Referring to these drawings, it will be seen that the base plate consists of two sections 10 and 11. Each of these sections is formed of a strip of metal having its margins bent over for nearly the entire extent of the strip, as at

12. One of these strips is adapted to be telescoped within the other strip and thus the two strips forming the base plate are adjustable upon each other. The flanges 11 are not extended the entire length of each strip but terminate short of the outer end of the strip. The margins of the strip at this outer end are turned flatly inward, as at 13, and the end of the strip is bent to form an upwardly extending hook 15.

Just outward of the ends of the flanges 11 there is provided an aperture or slot 16, and coacting with this end of the strip 10 is the shade roller supporting bracket 17 having a tongue 18 insertible through this aperture 16 and turned flatly against the inner face of the strip 10, the flanges 13 extending down flatly over this tongue. Thus the shade roller bracket 17 is held firmly in place against detachment. One of the shade roller brackets 17 is provided with the usual opening for the circular trunnion of the shade and the other with an open-ended slot for the reception of the rectangular trunnion of the shade.

Coacting with the base formed of the parts 10 and 11 is the curtain supporting rod formed of the sections 19 and 20. These also have their margins turned inward so as to provide the beads or flanges 21 and the section 19 telescopes within the section 20. The outer end of each section is angularly bent, as at 22, so as to fit over the corresponding hook 15 and this outstanding end 22 has a slot 23 formed at the junction of the turned over margin or flange 21 which engages with the bill 15^a of the upwardly turned hook 15 so that when the curtain supporting rod has its ends telescoped over the outwardly extending members or hooks 15, the bills 15^a will engage in these apertures 23 and lock the curtain supporting rods from detachment by being pulled directly outward.

The ordinary curtain supporting rod is not formed with apertures nor are the brackets for supporting this rod formed with upwardly extending hooks. As a consequence, the rods may pull directly off and it sometimes occurs that the mere weight of the curtains will act to pull these rods off, particularly after the rods have been taken off and

put on again a number of times. This is obviated in this construction as the hooks interlock with the extremities of the curtain supporting rod and any downward pull on the rod will, of course, tend to keep the curtain supporting member in its locked position upon the hooks of the base.

It will be seen that the beads or flanges 12 and 21 act to strengthen the base and the curtain supporting member. It will likewise be seen that the curtain supporting member has the flanges 12 on the inside face. The base is held in place upon the lintel of a window by means of screws or other attaching devices passed through holes 24 in the base, and it will be noticed that these holes are disposed close to the ends so that when the base is attached to the lintel any tendency of the flanges 12 or the flanges 13 to unfold or open out is prevented and thus the strain exerted by the weight of the shade upon the shade brackets 17 is resisted. Of course, it will be understood that the brackets 17 are to be used for holding the ordinary window shade, while the side curtains and valance may be supported upon the curtain support consisting of the sections 19 and 20.

It will be seen that I have provided a shade and curtain supporting device which is adjustable to windows of various widths and which provides a relatively long supporting base for the bracket which, while illustrated as being attached at two points, may be attached at more points to the lintel of the window. It will be seen that the curtain supporting portion composed of the sections 19 and 20 may be readily removed from the base and that the base will then support the shade. The curtain supporting portion is interlocked with the base so as to prevent accidental detachment. The parts are very simple and may be cheaply made, yet at the same time are rendered strong and rigid by the beads or flanges 12 on the base and the beads or flanges 21 on the curtain supporting rod. The shade supporting brackets are very readily engaged with the base and are then held engaged by the turning down of the flanges 13 against the tongue 18 of the bracket.

I claim:

In a shade roller support, a base of sheet metal having a transverse slit formed therethrough, a shade roller bracket adapted to be disposed upon said base and having a lateral tongue designed to be extended through said slit, the tongue being bent at right angles to the bracket, the base having lateral flanges bent inward upon the inside face of the base over said slit and the tongue inserted therethrough.

In testimony whereof I hereunto affix my signature.

FAYE B. HAMMOND.
